LABORATORY SWIVEL CLAMP OR SIMILAR ARTICLE

Frank P. Fritchle, Santa Ana, Calif., and Manning S. Reynolds and Earl K. Takata, Chicago, Ill., assignors to Central Scientific Co., Chicago, Ill., a corporation of Illinois

Application October 23, 1956, Serial No. 43,468

Term of patent 14 years

(Cl. D54—11)

Figure 1 is a front elevational view of a laboratory swivel clamp showing our new design;

Figure 2 is a front elevational view similar to that of Figure 1, with the left hand end swiveled 90 degrees;

Figure 3 is an end elevational view taken from the right of Figure 1, with the right hand end of the article swiveled 90° from the position of Figure 1;

Figure 4 is a top plan view of the article as shown in Figure 1, with the right hand end of the article swiveled 90° from the position of Figure 1;

Figure 5 is an end elevational view of the article taken from the left of Figure 1, with the right hand end of the article swiveled 90° from the position of Figure 1; and

Figure 6 is a view similar to that of Figure 5, with the left hand end of the article as shown in Figure 1 swiveled 90 degrees from the position of Figures 1 and 5, and with the right hand end of the article as shown in Figure 1 swiveled 180 degrees from the position of Figure 1.

The dominant features of the design reside in the portions shown in full lines.

We claim:

The ornamental design for a laboratory swivel clamp or similar article, substantially as shown and described.
